UNITED STATES PATENT OFFICE.

CHARLES A. PARFREY, OF RICHLAND CENTER, WISCONSIN.

HEN'S NEST.

Application filed January 24, 1922. Serial No. 531,424.

To all whom it may concern:

Be it known that I, CHARLES A. PARFREY, a citizen of the United States, and a resident of Richland Center, in the county of 5 Richland and State of Wisconsin, have invented a new and Improved Hen's Nest, of which the following is a full, clear, and exact description.

This invention relates to improvements in 10 hens' nests, an object of the invention being to provide a device of this character, which is collapsible so that it may be readily opened up for the purpose of cleaning and disinfecting the same.

15 A further object is to provide a collapsible nest of this character, formed almost entirely of wood, which will occupy a comparatively small amount of space when being shipped, and which may be readily as 20sembled and disassembled, as desired.

A still further object is to provide a highly sanitary device of the character stated, which will be simple and practical in construction, durable and efficient in use, 25 and comparatively inexpensive to manufacture.

With these and other objects in view, the invention consists in certain novel features 30 of construction and combinations and arrangements of parts as will be more fully hereinafter described and pointed out in the claims.

In the accompanying drawings:

Figure 1 is a view in front elevation of 35 my improved hen's nest;

Figure 2 is a top plan view thereof, parts being broken away and in section for clearness;

Figure 3 is a view in rear elevation of 40 the nest; and

Figure 4 is a collective view showing the various parts of the nest disassembled.

Referring in detail to the drawings, my improved nest comprises a bottom 1 and 45 front and rear sections 2 and 3 respectively hinged at their lower edges to opposite sides of the bottom 1 by conventional double jointed hinges 4, said front and rear sections being adapted to swing outwardly from the

50 bottom. The front section includes a plurality of uprights or standards 5, to which a base board 6 is attached. A connecting cross piece 7 is also secured to all of the standards adjacent their upper ends to 55 strengthen the construction of the nest, the

openings between the base board and the cross pieces providing entrances for the hens into the nest.

The rear section 3 in like manner includes a plurality of standards 8, to which 60 a rear wall 9 is secured. This wall is provided with a hinged door 10 so that access may be had to the nest through the rear wall thereof. The standards 5 and 8 are provided with aligned grooves on their inner faces receiving the edges of vertically 65 slideable partitions 11, which serve to divide the nest into a number of compartments. In order to prevent relative separation of the front and rear walls of the nest, I utilize 70 straps 12 formed of twisted wire and provided at their ends with loops 13 adapted to encircle the upper ends of the standards 5 and 8 respectively, to prevent the accidental collapsing of the nest and to securely hold 75 the partitions in place.

For the purpose of cleaning the nest, the straps and partitions may be removed, as seen in Figure 4, and the front and rear wall sections swung outwardly. Access may 80 thus be had to every part of the nest for the purpose of cleaning or exposing the same to the light.

It will be evident that the number of partitions in the nest might be varied to suit 85 the trade, and although I have illustrated one of the preferred embodiments of my invention, numerous slight changes and alterations might be made in the general form and arrangement of the parts described 90 without departing from the invention, and hence I do not wish to limit myself to the precise details set forth, but shall consider myself at liberty to make such slight changes and alterations as fairly fall within the 95 spirit and scope of the appended claims.

I claim:

1. In a hen's nest, a bottom, front and rear sections hinged to opposite sides of the bottom, said sections including uprights and 100 cross pieces connecting the uprights, and straps including looped ends encircling the upper ends of the uprights to prevent accidental separation of the sections.

2. In a hen's nest, a bottom, front and 105 rear sections hinged to opposite sides of the bottom, said sections including uprights and cross piece connecting the uprights, and straps including looped ends encircling the upper ends of the uprights to prevent acci- 110

dental separation of the sections, said uprights having vertical grooves therein, and partitions slideable vertically in the grooves.

3. A hen's nest comprising a bottom, a front hinged to the bottom and formed of uprights and top and bottom boards secured to the uprights, a rear wall having standards and hinged to the bottom, the rear wall being provided with a hinged door, cross tie members removably engaging the stand-

ards, and partitions having sliding engagement with the said uprights.

4. In a hen's nest, having a bottom, and front and rear sections hinged to the bottom, the said sections having uprights projecting above the sections, and tie straps formed of twisted wire having loops at their ends for encircling the upper ends of the uprights. 15

CHARLES A. PARFREY.
